UNITED STATES PATENT OFFICE

AMOS H. SWANDER, OF WORLAND, WYOMING

HEATING SYSTEM AND BOILER CONSTRUCTION

Application filed May 2, 1929. Serial No. 359,819.

This invention relates to steam or hot water boilers, and has for its principal object the provision of a boiler which will be highly efficient and in which the water will be 5 brought into direct and intimate contact with the heating medium.

Another object of the invention is to provide a boiler in which the boiler tubes can be quickly and easily inserted or removed for 10 renewal and repairs.

A still further object of the invention is to provide a boiler construction in which the boiler tubes will be effectively sealed to the heads without the use of riveting, welding, 15 and the like.

Other objects and advantages reside in the detail construction of the invention, which is designed for simplicity, economy, and efficiency. These will become more apparent 20 from the following description.

In the following detailed description of the invention reference is had to the accompanying drawing which forms a part hereof. Like numerals refer to like parts in all views 25 of the drawing and throughout the description.

In the drawing:

Fig. 1 is a side elevation of a heating plant in which the invention is embodied. In 30 this view the boiler and firepot have been partially broken away to show the interior construction.

Fig. 2 is an enlarged bottom view of the boiler looking upwardly from the line 2—2, 35 Fig. 1. In this view the tube plate 28 has been partially broken away to illustrate the extremities of the boiler tubes.

Fig. 3 is a still more enlarged cross section through the bottom of the boiler taken on the 40 line 3—3, Fig. 2.

The invention is more particularly applicable to heating plants of the type employed for heating radiation in buildings and the like, and may be applied to either steam 45 or hot water heating systems.

In systems of this nature it is generally necessary to maintain a relatively large supply of water but if all of this large volume 50 of water is admitted to the heating boiler simultaneously it can not come in effective

contact with the boiler tubes and heating surfaces, unless an excessively large boiler is employed.

In this invention, a relatively long, narrow boiler is employed, such as illustrated at 10 and an auxiliary water tank 11 is used to contain a supply of water for the boiler. By 55 this construction the water in the boiler 10 is brought in closer contact with the heating tubes and a smaller number of heating tubes 60 are required and a more efficient transfer of heat is obtained than if all of the water in both the boiler and the tank 11 was contained within the boiler.

By constructing the boiler 10 relatively 65 long and narrow the heat from the fire can be more effectively absorbed before the hot gases leave the boiler.

The boiler 10 is provided with the usual 70 appurtenances such as a water glass 12, pressure gauge 13, and safety valve 14, and is supported on a suitable firepot 15 in which preferably, but not necessarily, a gas burner 16 is arranged.

The hot water or steam flows to the radiators of the heating system from the boiler 10 through a feed main 17 and returns from the radiators through a return main 18 to the tank 11. The water flows from the bottom 75 of the tank 11 through a supply pipe 19 and a check valve 20 which prevents the return of water from the boiler to the tank 11.

The system operates in a closed circuit from the feed main 17, through the radiators, and into the return main 18. Thus, when the 80 steam is first turned into the feed main 17 it will condense in the system and flow back through the return main 18 to the tank 11. As the system heats condensation will lessen and steam will flow through the system to the tank 11 placing it under practically the same pressure as the boiler 10. When this 85 occurs the weight of the water in the tank 11 will cause it to flow from past the check valve 20 and into the boiler. By this arrangement injectors or boiler feed pumps are eliminated and the supply of feed is substantially automatic.

The heat from the burner 16 is conveyed 90 through the water in the boiler 10 in vertical 100

fire tubes 21 and discharges through a suitable stack 22. It is desired to call attention to the effective method employed for securing the fire tubes 21 in the boiler.

5 The boiler is, of course, provided with heads 23 which are preferably welded therein, as shown at 24. The tubes 21 in the usual installation are formed of malleable copper, and are of a length to extend slightly 10 beyond both the heads 23. The tubes 21 are passed through relatively tight tube holes in the heads 23 and the extending-beyond portions thereof are turned outwardly and crimped to form annular flanges 25. Soft 15 copper washers 26 surround the extremity of the tubes between the flanges 25 and the heads 23.

On each head 23 a series of spaced-apart stud bolts 27 are welded. A tube plate 28 is 20 passed over the studs 27 and is clamped in place by means of clamp nuts 29 thereon. The tube plate 28 is provided with flow openings 30 which register over each of the tubes 21. As the nuts 29 are tightened the tube 25 plate 28 will positively clamp the flanged extremities 25 of the tubes 21 and the washers 26 against the heads 23 so as to effectively seal the boiler at this point.

It is desired to call attention to the effectiveness of this method of tube installation. 30 No welding, riveting, caulking, or expanding is required. Any irregularities in the flange tubes will be flattened out and effectively sealed by the pressure of the tube plate 28.

35 Any imperfections in the length of the fire tubes 28 will be corrected by the pressure of the tube plate 28 should a tube be slightly longer than necessary it will be compressed and will shorten or bend slightly or will turn 40 outwardly more in its flange than the others as the nuts 29 are tightened. Thus, an effective job of installing boiler tubes can be accomplished by relatively unskilled labor.

Should it be necessary to remove any or 45 all of the tubes the nuts 29 can be quickly loosened and the plates 28 removed, allowing the damaged tubes to be withdrawn and new ones to be inserted without the use of special equipment or apparatus.

50 While a specific form of the improvement has been described and illustrated herein, it is desired to be understood that the same may be varied, within the scope of the appended claims, without departing from the spirit of 55 the invention.

Having thus described the invention, what I claim and desire secured by Letters Patent is:—

1. A boiler comprising: a boiler shell, 60 heads in each extremity of said shell having tube holes therein; tubes extending through said boiler and through said holes; flanges formed on said tubes on the outer faces of said heads; a tube plate provided with flow 65 openings for said tubes; and means for

clamping one of said tube plates against said flanges on each of said heads so as to seal said tubes to said heads.

2. A boiler comprising: a boiler shell, 70 heads in each extremity of said shell having tube holes therein; tubes extending through said boiler and through said holes; flanges formed on said tubes on the outer faces of said heads; a tube plate provided with flow openings for said tubes; studs projecting from said heads and arranged to extend through said tube plates and clamp the latter against said flanges. 75

3. In a boiler having a head with tube holes therein, means for securing boiler tubes in 80 said holes comprising: a flange formed in the extremity of said tube; means for clamping said flange against said head, said means comprising: a tube plate having a flow opening in alignment with said tube; and means for 85 clamping said tube plate against said flange.

4. In a boiler having a head with tube holes therein, means for securing boiler tubes in 90 said holes comprising: a flange formed in the extremity of said tube; means for clamping said flange against said head, said means comprising: a tube plate having a flow opening in alignment with said tube; and means for 95 clamping said tube plate against said flange, said latter means comprising: studs projecting from said head and arranged to pass through said plate; and nuts on said studs adapted to clamp against said plate.

In testimony whereof, I affix my signature.

AMOS H. SWANDER.
